J. BERLIEN.

STEERING WHEEL LOCK FOR AUTOMOBILES AND THE LIKE.

APPLICATION FILED DEC. 4, 1918.

1,318,842.

Patented Oct. 14, 1919.

Inventor:
John Berlien

UNITED STATES PATENT OFFICE.

JOHN BERLIEN, OF ST. LOUIS, MISSOURI.

STEERING-WHEEL LOCK FOR AUTOMOBILES AND THE LIKE.

1,318,842.

Specification of Letters Patent. Patented Oct. 14, 1919.

Application filed December 4, 1918. Serial No. 265,215.

To all whom it may concern:

Be it known that I, JOHN BERLIEN, a citizen of the United States, and resident of St. Louis, Missouri, have invented certain new and useful Improvements in Steering-Wheel Locks for Automobiles and the like, of which the following is a specification.

This invention relates to improvements in a steering wheel lock for automobiles and the like, and has for its object a locking mechanism attached to the steering column and positioned in close proximity to the steering wheel so that the wheel may be firmly locked whenever it is desired to park the machine.

A further object of my invention is to construct a lock the locking member thereby being reversible so as to retain the same in position when the lock is not in use and to reverse it with little difficulty for locking the steering wheel whenever it becomes necessary to do so.

Figure 1 is a view of a steering wheel and a portion of the steering column showing my invention in position thereon.

Fig. 2, is a front view of my improved lock.

Fig. 3, is a side view of the same.

Fig. 4, is a vertical sectional view of the same.

Fig. 5, is a horizontal sectional view taken on the line 5—5 of Fig. 2.

Fig. 6, is a detail view of a portion of the supporting frame showing the side which contacts with the steering column.

Fig. 7, is a detail perspective view of the reversible locking member.

Fig. 8, is a perspective view of the supporting frame in which the locking member is supported.

In the general construction of my invention I provide a suitable frame 9 which is constructed preferably of a casting of durable and tough material, the same being so arranged as to fit against the steering column 10 of an automobile, and the same is positioned on the column in close proximity to the steering wheel 11. This casting is firmly held on the column 10 by means of bands 12, which encircles the column. Its ends 13 are somewhat enlarged and are shaped to fit into the cavity or depressions 14 formed in the casting 9. The relative position of the parts being shown in Fig. 5.

The casting is firmly secured to the bands by the concealed screws 15, the heads of the

screws being concealed in the depression 16, and the same is entirely hidden from view or from access when the removable locking member 17 is placed in position on the casting 9. The casting is also provided on its outer surface with depressions 18. These are so arranged as to accommodate the insertion of the ears 19 formed on the locking member 17. The outer surface being arranged flush with the casting as that shown in Figs. 2 and 3, and the arrangement is such that the locking member 17 may be placed in either position as that shown in Fig. 1, by solid and dotted lines. The reversible locking member is also constructed in the form of a tough casting and is provided with an extension or arm 20 which terminates into a bifurcation 21, the arms of the bifurcation being arranged to snugly straddle the spokes 22 of the steering wheel, thus preventing the wheel from being turned and the body of the member 17 is provided with a lock casting 23 in which is placed a suitable lock of the standard type. This lock is generally of the pin or any other standard type and is in the form of a cylinder 24 as that shown in Fig. 2. The lock bar 25 of the lock is so arranged as to fit under the flange 26 formed on the cross-bar 27 which cross-bars have their contact surface 28 sufficiently curved to correspond with the curvature of the steering column 10. The cross bars 27 form a part of the casting 9 and are both shaped the same so that the lock bar 25 can either register with the top or the bottom one for holding the locking member in its proper set position.

The ends of the casting 9 are shaped and beveled as that indicated by the numeral 29 and against the inner bevel surface is adapted to contact an elongated tooth 30 which is formed on one end of the reversible lock member 17. This tooth is first inserted in position and then by turning the key of the lock the lock bar 25 will contact with the flange 26 thereby holding the locking member in locked position in the casting.

As shown in the illustration the locking member is inserted in the casting in the position for locking the steering wheel that is, bringing the bifurcated end in the position to straddle the spoke of the steering wheel. When it is desired to unlock the wheel so that the same can be used for manipulating the automobile then the reversible lock member is unlocked and reversed so

that the tooth 30 is brought in contact with the upper cross-bar 27 and the bifurcated end extending downwardly and as shown by the dotted lines in Fig. 1. The lock is then 5 manipulated and the key removed, this retains the locking member at all times in position so that it cannot become disconnected or lost.

The device is simple in character yet 10 firmly prevents the steering wheel from being turned thereby operating the steering mechanism of the automobile.

Having fully described my invention what I claim is:

15 1. A lock of the character described comprising a skeleton casting firmly attached to the steering column of an automobile and in close proximity with the steering wheel, a reversible member arranged to be inserted 20 in the supporting member, a lock for locking the same in position therein, and a bifurcated projection forming a part of the locking member which bifurcation straddles one of the spokes of the steering wheel, and 25 cross bars formed in the casting with which the reversible member is locked substantially as specified.

2. A device of the character described comprising a casting, the same provided 30 with flange cross-bars and a plurality of depressions in its face, bands supporting the casting on the steering column of an automobile, a locking member provided with

ears which are arranged to be inserted in the depressions of the casting, a lock tooth 35 formed on one end of the locking member and designed to contact with the inner edge of a portion of the casting, a lock located in the casting to contact with one of the cross-bars and a bifurcated extension forming a part of the locking member and which is designed to straddle one of the spokes of the steering wheel, substantially as specified.

3. A lock of the character described comprising a supporting casting which is rigidly supported to the steering column, cross bars formed in the casting against which the locking member is locked, a removable and reversible bifurcated locking member supported in the casting, a means formed on the locking member for engaging with the steering wheel and a lock for supporting the locking member in the casting either in locked or unlocked position, the arrangement of the members being such as to permit the locking member to be held and locked in a reverse position, substantially as specified.

In testimony whereof I have signed my 60 name to this specification, in presence of two subscribing witnesses.

JOHN BERLIEN.
